UNITED STATES PATENT OFFICE.

CHARLES AUGUSTUS DE RIGNE, OF LOS ANGELES, CALIFORNIA.

TIRE-PUMP.

1,323,168.

Specification of Letters Patent.

Patented Nov. 25, 1919.

Application filed December 2, 1918. Serial No. 264,948.

To all whom it may concern:

Be it known that J. CHARLES A. DE RIGNE, a citizen of the United States, residing at Los Angeles, in the county of Los Angeles and State of California, have invented certain new and useful Improvements in Tire-Pumps; and I do declare the following to be a full, clear, and exact description of the invention, such as will enable others skilled in the art to which it appertains, to make and use the same.

My invention relates to improvements in air pumps and more particularly to those designed for inflating pneumatic tires. The object of the invention is to provide a pump of comparatively simple and inexpensive construction, yet one which will be highly efficient and easy to operate, provision being made whereby an extremely large area is allowed for the air to pass into the cylinder in front of the piston as the latter is moved on its receding stroke.

With the foregoing object in view, the invention resides in the novel features of construction and unique association of parts hereinafter fully described and claimed, reference being made to the accompanying drawing which forms a part of this application.

In the drawing Figure 1 is a vertical longitudinal section of the pump and Fig. 2 is a transverse horizontal section on the plane of the line 2—2 of Fig. 1.

In the drawing above briefly described, the numeral 1 designates a pump cylinder whose lower end is shown mounted in a threaded socket 2 having a foot piece 3, an outlet nipple 4 being provided from a chamber 5 in the bottom of the socket 2, and the usual flexible tube 6 leads from the nipple 4 for attachment to the tire valve. The upper end of cylinder 1 is provided with a cap 7 suitably secured in place and provided with a central opening 8 and with a number of apertures 9, the latter being for the purpose of permitting the intake and discharge of air into the cylinder as the pump piston is reciprocated, thereby preventing the compression of air above the piston or the creation of a partial vacuum, either of which would retard the operation of the pump.

A hollow piston head 10 is provided in the cylinder 1, the periphery of said head being provided near its upper end with an external shoulder 11 against which the in-

wardly turned edge of a packing ring 12 is clamped by means of a collar 13 which surrounds the head, said collar being interposed between the packing and head as shown. A nut 14 is shown for the purpose of securing the collar 13 in place, but other adequate provision might well be made for this purpose. The upper end of the piston head 10 is provided with a hollow neck 15 into which the lower end of a tubular piston rod 16 is threaded, said head passing slidably through the opening 8 and being connected by a tubular plug 17 with a handle 18. At 19, the rod 16 is perforated so that as the handle is raised, air will enter the pump through these perforations and through the tubular plug 17, such air traveling through the head 10 to be compressed by the piston on its descending stroke. A novel arrangement of valves is provided in the piston to allow the air to descend but to prevent any upward leakage when the piston is depressed.

The valve arrangement above mentioned is preferably as shown. The bottom or lower end 20 of the piston head 10 is provided with a cone valve seat 21 facing downwardly, and above said bottom the head is provided with a spider 22. A cone or puppet valve 23 engages the seat 21 and is provided with a tubular stem 24 rising into the head 10 and guided by the spider 22, a spring 25 being provided around said stem to normally close the valve. One end of the spring preferably abuts the spider 22 while the other end thereof bears against a pin or the like 26 carried by the stem 24. At its center, the lower side of valve 23 is provided with a cone valve seat 27, and above this seat with a spider 28, said seat receiving a relatively small cone valve 29 whose stem 30 slides within the spider 28 and is provided with a spring 31 engaging said spider to normally seat the valve.

By the provision of the valve structure above described, when the piston is raised, both valves 23 and 29 will open, thus providing an unusually large area through which the air may flow into the lower end of the cylinder. This causes extremely easy operation of the pump since the ascent of the piston encounters no resistance other than the friction of the piston upon the cylinder, which is infinitesimal. Also, should one of the valves bind for any reason and fail to open, the other will operate,

thus preventing trouble and inconvenience which would otherwise be caused even though the binding were momentary.

From the foregoing, taken in connection with the accompanying drawings, it will be seen that although my invention is of simple and inexpensive nature, it will be highly efficient and in every way desirable, and on account of the advantages derived therefrom, the construction shown and described is preferable. It is to be understood, however, that within the scope of the invention as claimed, numerous minor changes may well be made without departing from or sacrificing any advantages of the invention.

I claim:

A pump piston comprising a one piece hollow cylindrical piston head having an outwardly facing cone valve seat at one end 20 and an outwardly projecting tubular neck integral with its other end for the attachment of a tubular piston rod, a spider extending across said hollow piston head and having a central guide opening, a tubular 25 valve stem sliding through said guide open-

ing and having its inner end positioned loosely in said tubular neck and provided with a stop pin, the outer end of said tubular valve stem having an external cone valve and an internal cone valve seat, said valve coacting with the seat of said piston head, a coiled spring surrounding said tubular valve stem between said spider and said stop for normally seating said cone valve, a second spider extending across said tubular valve stem and having a central guide opening, a relatively small valve stem sliding through said guide opening of the second spider, a cone valve on the outer end of said relatively small stem for coaction 40 with the valve seat of said tubular stem, a stop on the inner end of said relatively small stem and a coil spring surrounding this stem between its stop and guiding spider.

In testimony whereof I have hereunto set 45 my hand.

CHARLES AUGUSTUS DE RIGNE.
